UNITED STATES PATENT OFFICE

141,109

DESIGN FOR A KNIFE

Sundel Doniger, New York, N. Y.

Application January 12, 1945, Serial No. 117,393

Term of patent 14 years

(Cl. D22—3)

To all whom it may concern:

Be it known that I, Sundel Doniger, a citizen of the United States, residing at New York, in the county of New York and State of New York, have invented a new, original, and ornamental Design for a Knife, of which the following is a specification, reference being had to the accompanying drawing, forming part thereof.

In said drawing,

Figures 1 and 3 are elevational views looking at opposite sides of a knife showing my new design;

Figures 2 and 4 are top and bottom edge views respectively of the knife; and

Figures 5 and 6 are end views of the knife.

I claim:

The ornamental design for a knife, as shown.

SUNDEL DONIGER.
